UNITED STATES PATENT OFFICE.

CHARLES W. DOHM, OF BALTIMORE, MARYLAND, ASSIGNOR TO THE CONTINENTAL ROOFING AND MANUFACTURING COMPANY, OF BALTIMORE, MARYLAND, A CORPORATION OF MARYLAND.

DESIGN FOR A SHINGLE STRIP.

Application filed June 3, 1925. Serial No. 13,649. Term of patent 14 years.

To all whom it may concern:

Be it known that I, CHARLES W. DOHM, a citizen of the United States, residing in the city of Baltimore, State of Maryland, have invented a new, original, and ornamental Design for a Shingle Strip, of which the following is a specification, reference being had to the accompanying drawing, forming part thereof.

In the drawing:

Fig. 1 represents a plan view of a shingle strip showing my new design.

I claim:—

The ornamental design for a shingle strip as shown.

CHARLES W. DOHM.
